FIG-4

FIG. 1 is a front perspective view of a door embodying my new design;

FIG. 2 is a front elevational view of a fragment of the complete design shown in FIG. 1;

FIG. 3 is a fragmentary section taken as indicated by the line 3—3 of FIG. 2; and

FIG. 4 is an elevation of the door as seen from the rear of FIG. 1.

The dominant features of my design reside in the specific arrangement of the applique pattern.

I claim:

The ornamental design of a door, as shown and described.
